UNITED STATES PATENT OFFICE

154,536

DESIGN FOR AN AUTOGRAPH BOOK

Lucille M. Forschner, East Cleveland, Ohio

Application February 28, 1947, Serial No. 137,231

Term of patent 7 years

(Cl. D6—2)

To all whom it may concern:

Be it known that I, Lucille M. Forschner, a citizen of the United States, residing at East Cleveland, in the county of Cuyahoga and State of Ohio, have invented a new, original, and ornamental Design for an Autograph Book, of which the following is a specification, reference being had to the accompanying drawings, forming part thereof. The stitching shown in Figs. 1 and 3 is provided on the back of the book.

Fig. 1 is a plan view of an autograph book, showing my new design.

Fig. 2 is an elevational view.

Fig. 3 is a plan view of the book in an open position.

I claim:

The ornamental design for an autograph book, as shown and described.

LUCILLE M. FORSCHNER.
